UNITED STATES PATENT OFFICE.

CHARLES LENARDIĆ, OF CLEVELAND, OHIO.

RAIL-CONNECTING DEVICE.

1,231,392.

Specification of Letters Patent. Patented June 26, 1917.

Application filed February 26, 1917. Serial No. 151,084.

To all whom it may concern:

Be it known that I, CHARLES LENARDIĆ, a subject of the King of Hungary, residing at Cleveland, in the county of Cuyahoga and State of Ohio, have invented certain new and useful Improvements in Rail-Connecting Devices, of which the following is a specification.

This invention relates to certain new and useful improvements in rail connecting devices.

The primary object of the invention is the provision of a ready means for detachably connecting together the adjacent ends of railway rails in their operative assembled relations, the structure being such as not to require the use of any bolts or screws and readily operable by hand without the employment of tools.

20 A further object of the device is the provision of a rail connecting means whereby rails are securely connected together in hand engagement for use upon the road bed and may be readily disconnected by hand when desired, the same being especially serviceable for use with temporary tracks, such as those employed for excavators and under similar circumstances.

With these general objects in view and others that will appear as the nature of the invention is better understood, the same consists in the novel construction, combination and arrangement of parts hereinafter more fully described, illustrated in the accompanying drawings and then claimed.

In the drawings forming a part of this application and in which like designating characters refer to corresponding parts throughout the several views:—

40 Figure 1 is a side elevation of the device operatively arranged connecting two rails together.

Fig. 2 is a central longitudinal sectional view thereof.

45 Fig. 3 is a vertical transverse sectional view taken upon line III—III of Fig. 1.

Fig. 4 is a similar view taken upon line IV—IV of Fig. 2.

50 Fig. 5 is a perspective view of one of the locking plates employed, and,

Fig. 6 is an elevational view partially broken away of one of the locking pins removed.

55 The device is illustrated herein in connection with the adjacent end portions of two railway rails 10 and 11 positioned in end

engagement with each other as ordinarily employed when positioned in track formation. The web 12 of each rail is provided with two transverse slots 13 arranged in the same spaced relations.

Two locking plates 14 of the form best shown in Fig. 5 of the drawing are employed for connecting the rails together, the said plates, each having a fish plate portion 15 with a flanged base 16 for flatly engaging over the base flange 17 and against the web 12 of the adjacent rail while slots 18 are arranged therein positionable in alinement with the slots 13 of the adjacent rail web. An extension 19 projects in longitudinal alinement from the upright portion 15 of each plate 14, parallel arms 20 being carried by said extension perpendicular thereto and adapted for projecting through the slots 13 of the web of the adjacently positioned rail, such as 10, when the slots 18 of the plate are in alinement with the slots 13 of the web of the rail 11 and also through the slot 18 in the locking plate. This arrangement is best illustrated in Fig. 2 of the drawing, a locking pin 21 being provided at each side of the device adjacent the plate portions 15 for insertion through perforations 22 in the said arms 20, a head 23 being provided upon the pin 21 at one end thereof. A lever 24 is pivoted to the opposite end of the pin 21 from the head 23 and adapted to be swung at right angles to the said pin for preventing the latter from being removed from the opening 22. A serrated heel 25 is provided upon the lever 24 for engagement with the face of the adjacent plate portion 15 for retaining the pin in position.

The operation of the device will be understood from this detailed description thereof, the positioning of the two plates 14 upon the rails 10 and 11 having been set forth as well as the projecting of the arms 20 through the slots 13 of the rail web, the pin 21 being readily inserted and retained in position by moving the levers 24 pivotally to points perpendicular with respect to the plate portions 15, the pins and plates being readily removed from the rails in substantially an opposite manner, thereby disconnecting the rails.

What I claim as new is:—

1. A connector for rails comprising two plate members oppositely positioned in contact with the opposite faces of abutting rails, arms carried by each of said members adapt-

ed for projecting through the adjacent rails and the adjacently positioned coöperating plate, removable locking pins carried by the said arms and retaining levers pivoted to the 5 said pins having frictional retaining engagement with the face of the adjacent plate.

2. A device of the class described comprising in combination with railway rails adapted for end abutment and having equally 10 spaced apart slots through the webs thereof, securing plates adapted for engagement with the said rails upon the opposite sides thereof arranged with slots in alinement with the said web slots, perpendicularly projecting

arms carried by the said plates spaced apart 15 a distance equal to the distance between all of the said slots and adapted to project through the alining pairs of slots of the rail webs and plates, headed pins adapted for locking insertion through the said arms, and 20 pivoted retaining levers upon the unheaded ends of said pins having serrated heels adapted for frictional contact with the adjacent plate when the device is operatively arranged.

25 In testimony whereof I affix my signature.

CHARLES LENARDIČ.

Copies of this patent may be obtained for five cents each, by addressing the "Commissioner of Patents, Washington, D. C."
